[57] CLAIM

The ornamental design for a convertible bench, as shown and described.

DESCRIPTION

FIG. 1 is a front perspective view of a convertible bench showing my new design incorporated in a footstool;

FIG. 2 is an end elevational view thereof;

FIG. 3 is a front elevational view thereof;

FIG. 4 is a plan view thereof;

FIG. 5 is a front perspective view of a convertible bench showing my new design incorporated in a bench-like seat;

FIG. 6 is a front perspective view of the convertible bench of FIG. 5 but shown in converted position for use as a cocktail table.

FIG. 7 is an end elevational view thereof;

FIG. 8 is a front elevational view thereof; and

FIG. 9 is a plan view thereof.
